UNITED STATES PATENT OFFICE.

VERNON JAY KING, OF LORAIN, OHIO.

ENGINE-STOP.

No. 883,029.

Specification of Letters Patent. Patented March 24, 1908.

Application filed May 3, 1907. Serial No. 371,638.

To all whom it may concern:

Be it known that I, VERNON JAY KING, a citizen of the United States, residing at Lorain, in the county of Lorain and State of Ohio, have invented new and useful Improvements in Engine-Stops, of which the following is a specification.

This invention relates to an engine stop of that type which can be controlled from a 10 suitably remote point to cut off the supply of motive fluid to the engine under emergency conditions and thereby prevent the engine from running away and causing destruction.

The invention has for one of its objects to 15 improve and simplify the construction and operation of devices of this character so as to be comparatively easy and inexpensive to manufacture and install, and thoroughly reliable and efficient in use.

20 A further object of the invention is to provide a cut-off valve in the steam supply pipe that is actuated by the falling of a weight connected through a cable with a drum on the stem of the valve, the drum being normally held in locked position by a suitable 25 device controllable from any convenient point, as for instance, the engineer's office or similar place.

Another object is the provision of a locking device for controlling the drum on the 30 valve stem which device is mounted on a bracket adapted to be attached to the steam supply pipe and associated with the device is an electro-magnet which, when actuated, 35 releases the locking device so as to permit the drum to rotate under the action of the weight or equivalent motor.

With these objects in view and others, as 40 will appear as the description proceeds, the invention comprises the various novel features of construction and arrangement of parts which will be more fully described hereinafter and set forth with particularity in the claims appended hereto.

45 In the accompanying drawing, which illustrates one of the embodiments of the invention, the figure is a side elevation of the apparatus.

50 Referring to the drawing, 1 designates a steam supply pipe having a cut-off valve 2 of any approved construction, there being arranged on the stem 3 of the latter a drum 4 and a hand wheel 5. Suitably attached to the stem and supply pipe 1 is a bracket 6 on 55 which is fulcrumed at 7 a bell crank lever 8 having one arm bent into a pawl or dog 9

disposed over the drum and adapted to engage in a notch 10 in the rim of the latter, whereby the drum is prevented from moving when the apparatus is in set or operative position. Attached to the drum to wind and unwind on the latter is a cable 11 which passes over suitably arranged pulleys 12 and 13 to and around a pulley 14 attached to weights 15, the end of the pulley being anchored at 16 on a bracket 17. The weight is connected with a cross piece 18 that moves up and down on guide rods 19 which are connected by a cross piece 20 at their lower ends and are provided with cushioning devices or 60 helical springs 21 arranged on the guide rods whereby the weight 15 in falling, is cushioned and brought gradually to rest. This guide frame for the weight may be arranged on the ceiling of the engine room or at any 65 other convenient point and constitutes a monitor for quickly closing the valve as soon as the locking device or pawl 9 is released from the drum.

The locking device for the drum can be 70 operated in any suitable manner and in the present instance, the lever 8 is actuated by a contractile spring 22 anchored at one end of the bracket 6. The lever 8 is held in set position by a latch 23 fulcrumed at 24 on the 75 bracket and arranged so as to engage behind the extremity of the upright arm of the lever and disposed under the latch, is a spring stop 25 against which the lever strikes when the latch is released. On the bracket 6 at its 80 upper end is an electro-magnet 26 having a core 27 and an armature 28 that is hingedly connected with the latch. This electro magnet is connected in circuit with a suitable source of current and which circuit includes a switch located in the engineer's 85 office or other suitable point, whereby the electro magnet can be energized when it is desired to bring the engine suddenly to rest.

In practice, the parts are in the position 90 shown in the figure and when under any emergency condition, it is desired to stop the engine, the circuit including the electro magnet 26, is closed whereupon the armature 28 is drawn inwardly and the latch released from the lever so that the latter moves to the dotted line position to disengage the dog 9 from the drum. The weights will immediately drop and thereby rotate the drum and cause the valve to close with the consequent effect that the engine will be shut 105 down. When the emergency conditions of

the apparatus, necessitating the shutting down on the engine, have been overcome, the valve can be again opened by turning the hand wheel 5, which simultaneously winds 5 up the cable 11 on the drum 4 and raises the weights to normal position. While the wheel 5 is held, the lever is drawn forwardly so as to engage the dog 9 in the notch of the drum, and as the lever is drawn forwardly, 10 the latch 23, together with the armature 28, will drop behind the lever and hold it in set position. The dropping of the latch 23 is limited by the stop 25. From this, it will be seen that the valve can be opened and the 15 apparatus set in a simple and convenient manner, and that the device can be unlocked to permit the closing of the valve when occasion requires.

From the foregoing description, taken in 20 connection with the accompanying drawing, the advantages of the construction and of the method of operation will be readily apparent to those skilled in the art to which the invention appertains, and while I have described 25 the principle of operation of the invention, together with the apparatus which I now consider to be the best embodiment thereof, I desire to have it understood that the apparatus shown is merely illustrative and 30 that such changes may be made when desired, as are within the scope of the claims.

Having thus described the invention, what I claim is:—

1. In an apparatus of the class described, 35 the combination of a supply pipe, a valve therein, a drum on the stem of the valve, a bracket on the supply pipe, a locking device on the bracket directly engaging the drum, a latch fulcrumed on the bracket, an electro magnet controlling the latch, and a motor connected with the drum for actuating the valve.

2. In an apparatus of the class described, 45 the combination of a supply pipe, a valve therein, a bracket on the valve, a locking device mounted on the bracket, a spring tending to unlock the said device, a latch mounted on the bracket and adapted to engage the device, an electro magnet provided with an armature hingedly connected 50 with the latch, and a motor for closing the valve when the said device is unlocked.

3. In an apparatus of the class described, the combination of a supply pipe, a valve therein, a support on the pipe, a bell crank 55 lever having one arm formed into a dog, a spring for actuating the lever, a latch mounted on the support and arranged to engage behind one arm of the lever, a stop for the latch and lever, an electro magnet having an 60 armature hingedly connected with the latch a drum on the stem of the valve engaged by the dog, a motor for turning the valve in one direction when the dog is released, and a wheel attached to the drum for turning 65 the valve in the opposite direction.

4. In an apparatus of the class described, the combination of a supply pipe, a valve therein, a drum on the stem of the valve, a hand wheel connected with the valve, a 70 cable adapted to wind on the drum, a weight attached to the cable, pulleys over which the cable passes means for guiding the movement of the weight, and cushioning devices for checking the fall of the weight. 75

5. In an apparatus of the class described, the combination of a pipe, a valve therein, a drum on the stem of the valve, a weight, and a flexible element arranged to wind and unwind on the drum and connected with 80 the weight, with a bracket mounted on the pipe and provided with spaced arms, a bell crank lever fulcrumed on one of the arms and provided with a pawl for interlocking with the drum, a spring attached to the 85 bracket and lever for disengaging the pawl, an electro-magnet disposed between the arms and supported on the one opposite from that having the lever, a latch hinged on the bracket and adapted to engage behind the 90 free end of the lever, a core for the electro-magnet hingedly connected with the outer end of the latch and serving as a weight for holding the latch in normal position behind the lever, and a yielding stop on the bracket arranged to support the latch in normal position and to receive the lever when the latter is released. 95

In testimony whereof, I affix my signature in presence of two witnesses.

VERNON JAY KING.
